Filed May 5, 1972, Ser. No. 250,864

Term of patent 14 years

Int. Cl. D16—06
U.S. Cl. D57—1 C

FIG. 1 is a front elevational view of my design for an eyeglass holder;

FIG. 2 is a side elevational view of the holder; and

FIG. 3 is a top plan view of the holder.

The characteristic feature of my design resides in the height of the box-like receptacle portion which is almost equal to the length of a standard pair of spectacles in the folded state.

I claim:

The ornamental design for an eyeglass holder, substantially as shown and described.
